UNITED STATES PATENT OFFICE.

THOMAS BOVEY, OF CHICAGO, ILLINOIS.

DOORSTOP.

Application filed December 10, 1925. Serial No. 74,659.

Heretofore the keeping of doors of garages, barns and outhouses of all kinds, particularly, when subject to the wind, has required the employment of braces, usually consisting of 5 strips of wood or broken limbs of trees, picked up at random from the surrounding ground or floor.

The object of my invention is to provide a brace that is pivoted to the door, that can 10 be lowered to keep the doors open at any angle, wherever desired, and which can be lifted and held in its raised position without any particular effort.

This I accomplish by means hereinafter 15 fully described, and as particularly pointed out in the claims.

In the drawings:

Figure 1 is a perspective view of an open 20 garage door, showing my invention applied thereto.

Figure 2 is a bottom view of the retainer in which the brace or rod is caught when it is lifted to the limit of its raised position.

Figure 3 is a front edge view of the same.

25 Figure 4 is a side view thereof.

Figure 5 is a perspective view of the pivot plate that secures the rod to the door.

In the drawings A represents a rod, preferably of steel, which is, preferably square in 30 cross section. This rod is of a suitable length, say two feet long, and the end *a* that engages the ground is sharpened, or bevelled, and its opposite end is pivoted between a couple of corresponding lugs *b*, *b*, integral with and 35 projecting from a screw-plate C, which latter is attached to the inside surface of a door D, at a point near the outer edge thereof, and at a point, less than the length of the rod, above the ground or floor. This screw-plate 40 is preferably made of a rectangular piece of sheet metal, the longer edges of which are, between the ends thereof, bent outwards to form the pivotal-lugs *b*, *b*. Any suitable means for pivoting one end of said rod to the 45 door will, however, be satisfactory.

To hold the door open in the position desired the sharpened end of the rod is dropped until it engages and sticks into the ground or floor. When it is desired to release the door, 50 the lower sharpened end of said rod is lifted until it strikes the door above its pivot where it engages and is held by a suitable retainer. This retainer is made from a piece of flat metal E, that is provided with a couple of 55 screw-lugs *d*, *d*, projecting from one transverse edge, at, say, approximately ninety de-

grees to each other. This is accomplished by bending piece E V-shaped, so that the longer sides are at an angle of say ninety degrees to each other, and so that the angle of said bend 60 will strike between lugs *d*, *d*. When the piece is secured to the door, at a point a little less than the length of the rod above pivotal plate C, the bent side portions *e*, *e'*, of piece E will project forwards. The outer end of portion 65 *e* is, preferably, cut off square, but the outer end of the other portion *e'* is curved from its outer right hand corner toward its inner straight edge to serve as a guide, to direct said rod into a nest *m*, between said straight 70 edge and the inner straight edge of the other truncated portion *e*.

These straight edges are opposite each other and are parallel and separated the width of rod A, which is designed to rest between 75 them when locked. In order to retain the rod in said nest, there is a latch G, that is engaged by the rod as it enters the nest *m* between portions *e*, *e'*. This latch consists of an L-shaped member that is stamped out of a 80 single piece of sheet metal, and is pivoted by a rivet *g* near its inner angle, to the underside of portion *e*, so that the transverse edge of the inner shorter arm of the latch will, before rod A strikes it, project slightly in front 85 of the inner transverse edge of the nest.

The width of this shorter arm is such that, when the latch member is moved towards the door, its rear transverse edge engages the lug *d* back of it, and its movement will be limited 90 thereby.

The longer arm of said latch, projects forward beyond the front truncated edge of portion *e*, and is made wider and forms a head *h*, that has its forward edge curved or 95 cammed in a direction towards the cammed edge of portion *e'*. This curved portion of the head serves as a guide against which the rod strikes at the same time it engages the curved edge *f* of portion *e'*. The inner end of this 100 curved edge terminated in a shoulder *k*, the outer angle of which projects slightly in front of the entrance of the nest *m* that is occupied by the rod when the latter is at the limit of its raised position.

When it is desired to raise and retain the 105 rod A, it is grasped, below the pivotal-plate C, and lifted until its upper end portion strikes the head of the latch. As it strikes the curved edge of the head of this latch it forces the latter aside until it passes shoulder *k*, thereof 110 and the latch immediately gravitates back to

its original position, so that said shoulder *k* thereof is moved in front of the rod *A* and prevents its withdrawal from the nest. In order to release the rod, the latch is pushed or moved by hand until the shoulder *k* is away from the front of the same, whereupon said rod can be moved forward and dropped until its sharpened end again engages the ground or floor.

10. If desired the shoulder *k* can be inclined upwards slightly, as shown in Figs. 2 and 3, to assist the passage of the rod and to prevent its catching the clothes of the passerby. By inclining portion *e*, the latch, when not in use, will gravitate into such position as to leave the nest open and ready for the rod when it is desired to retain the same again.

What I claim as new is:—

1. A door-stop comprising a rod pivoted at one end to the inside of a door, in combination with a retainer comprising a suitable screw-plate fastened to the inside of the door above the pivotal point of the rod, a pivotal automatic latch member projecting from said plate and movable by gravity in a plane inclined slightly to the horizontal, the rod engaging portion of which is normally in the path of the rod and which is pushed aside by said rod when the latter is raised to the limit of its uppermost position, and automatically returns to its original position to retain said rod.

2. A door-stop comprising a rod pivoted at one end to the inside of the door, in combination with a retainer comprising a suitable screw-plate fastened to the inside of the door above the pivotal point of the rod, and a pivoted latch projecting laterally from said plate and movable by gravity in a plane inclined slightly to horizontal, which latch when the latter is raised to the limit of its uppermost position gravitates to its original position to retain the rod.

3. A door-stop comprising a rod pivoted at one end to the inside of a door, in combination with a retainer consisting of a mounting plate secured to the door above the pivot of the rod, a pair of spaced lugs projecting laterally from said plate and adapted to receive the rod when the latter is raised, and a pivoted latch member coacting with said lugs and having a hooked forward portion adapted to be engaged by the rod to move the latch member on its pivot to permit positioning of the rod between the lugs, said latch member having a shoulder back of its hooked end that is engaged by the rod after passing the hooked portion whereby to return the latch member to normal position with the hooked portion in front of the rod to retain the latter between said lugs.

4. A door-stop comprising a rod pivoted at

one end to the inside of a door, in combination with a retainer comprising a screw-plate having two screw-lugs projecting from its rear transverse edge that are secured to the inside of a door above the pivotal point of the rod and having two suitable forwardly projecting and separated portions that are bent V-shaped to each other, and a latch pivoted to the underside of one of said portions having its forward end pointed and projecting in front of said portion and has a shoulder on its inner edge.

5. A door-stop comprising a rod pivoted at one end to the inside of a door, in combination with a retainer consisting of a screw-plate having two screw-lugs projecting from the rear transverse edge thereof that are secured to the inside of a door above the pivotal point of said rod, and having two suitable forwardly projecting and separated portions, and a latch pivoted to the underside of one of said portions and having its forward pointed end projecting in front of the forward end of the portion to which it is pivoted, which has a shoulder on its inner edge, and whose rear edge engages the screw-lug back of it to limit its movement.

6. A door-stop comprising a rod pivoted at one end to the inside of a door, in combination with a retainer comprising a screw-plate having two screw-lugs projecting from the rear edge thereof that are secured to the inside of a door above the pivotal point of said rod, and has two suitable forwardly projecting and separated portions that are bent V-shaped to each other, and a latch pivoted to the underside of one of said portions and has its forward pointed end projecting in front of the portion to which it is pivoted that has a shoulder on its inner edge, and whose rear edge engages the screw-lug back of it to limit the movement.

7. A door-stop comprising a rod pivoted at one end to the inside of a door, a screw-plate consisting of a piece of sheet metal the original rectangular shape of which has its vertical edges bent forward between the upper and lower ends thereof between which said rod is pivoted, in combination with a retainer comprising a suitable screw-plate fastened to the inside of the door above the pivotal point of the rod, and a pivoted latch projecting laterally from said plate which latch is pushed aside by said rod when the latter is raised to the limit of its uppermost position, and is gravitated back to its position to retain said rod.

Signed at Chicago, in the county of Cook, and State of Illinois, this 24th day of November, 1925.

THOMAS BOVEY.
